US00D839338S

(12) **United States Design Patent** (10) **Patent No.:** **US D839,338 S**
(45) **Date of Patent:** **** Jan. 29, 2019**

(54) **MONITORING CAMERA**

(71) Applicant: **AXIS AB**, Lund (SE)

(72) Inventors: **Henrik Persson**, Lund (SE); **Fredrik Axelsson**, Loddekoinge (SE); **Andreas Hertzman**, Helsingborg (SE); **Gert Nilsson**, Sjöbo (SE); **Daniel Ahman**, Lomma (SE); **Mathias Walter**, Arlov (SE); **Morten Bergstrom**, Bjarred (SE)

(73) Assignee: **AXIS AB**, Lund (SE)

(**) Term: **15 Years**

(21) Appl. No.: **29/643,104**

(22) Filed: **Apr. 4, 2018**

Related U.S. Application Data

(60) Continuation of application No. 29/603,374, filed on May 9, 2017, which is a division of application No. (Continued)

CLAIM

The ornamental design for a monitoring camera, as shown and described.

DESCRIPTION

FIG. 1 is a perspective view of a monitoring camera showing our new design;

FIG. 2 is a left side view thereof;

FIG. 3 is a top plan view thereof;

FIG. 4 is a front elevational view thereof;

FIG. 5 is a rear elevational view thereof;

FIG. 6 is a right side view thereof; and,

FIG. 7 is a bottom plan view thereof.

The broken lines depict portions of the monitoring camera that form no part of the claimed design.

The parts shown with broken lines represent portions of the monitoring camera that form no part of the claimed design.

1 Claim, 4 Drawing Sheets

Related U.S. Application Data

29/564,737, filed on May 16, 2016, now Pat. No. Des. 811,462.
